UNITED STATES PATENT OFFICE.

WILLIAM S. TURNER, OF CONROE, TEXAS, AND ALBERT N. LONG, JR., OF GREENSBURG, PENNSYLVANIA; SAID LONG ASSIGNOR TO SAID TURNER.

TELEPHONE.

Application filed February 8, 1926. Serial No. 86,814.

The present invention relates to electro-magnetic telephones, and more particularly electro-magnetic reproducing devices of the kind commonly employed for radio purposes, although it is not limited to use in connection with radio. The invention is more especially adaptable to the so-called "loud speaker" units where the current values are relatively high, but is also applicable to the usual type of ear phone.

In the ordinary telephone, there is but a single winding of wire on the magnetic pole piece, and this winding is usually connected in a direct current circuit. Since it is in a direct current circuit, the armature or diaphragm is attracted or biased as long as the receiver is in the circuit. This biasing or constant attraction of the armature or diaphragm is not desirable because it interferes with the normal vibration of the armature or diaphragm in response to the current variations passing through the winding.

If the usual receiver is connected in an alternating current circuit rather than in a direct current circuit, it does not function to the best advantage because the windings, which are arranged for direct current, are not suitable for alternating current impulses.

According to the present invention, it is proposed to provide a receiver having specially arranged windings on the pole pieces particularly adaptable for use in alternating current circuits. A further object of the present invention is to provide, in combination with a radio or other circuit, a receiver especially adapted to respond to alternating current impulses, and to provide a circuit wherein the receiver is energized by alternating currents and protected against direct currents.

The invention may be readily understood by reference to the accompanying drawings, which illustrate a preferred embodiment of the invention, but the invention is not limited to the particular construction and arrangement of parts herein disclosed, as various other embodiments may be made within the spirit and contemplation of our invention.

In the drawings—

Figure 1 is a diagrammatic view illustrating a vertical section through a telephone receiver embodying my invention;

Figure 2 is a plan view of the receiver dis-

closed in Figure 1 with the diaphragm of the receiver removed;

Figure 3 is a diagrammatic view illustrating another arrangement of windings on the pole pieces of a receiver; and

Figure 4 illustrates a radio or thermionic tube circuit having an alternating current receiver connected therewith.

Referring to the construction shown in Figures 1 and 2 of the drawings, 2 designates a casing of any suitable construction, 3 is the diaphragm or armature of the reproducer, and 4 designates a cap which closes the casing and retains the armature in place. This arrangement is similar to the common telephone receiver, but it will be apparent that the invention is not limited to this particular arrangement of armature and casing.

Within the casing are pole pieces 5 and 6 arranged in the usual manner. The pole piece 5 is provided with two separate windings 7 and 8. The winding 7 is at one end of the pole piece, and the winding 8 is preferably at the other end of the pole piece. The turns of wire in the winding 8 are reversed to those in the winding 7.

On the pole piece 6 are also two windings 7' and 8' arranged similarly to the windings on the pole piece 5, but on reverse ends of the pole piece with respect to the windings on pole piece 5. In other words, the winding 7' which corresponds with the winding 7 in the direction in which it is wound is at the lower end of the pole piece 6 in Figure 1, while the winding 7 on the pole piece 5 is at the upper end. The windings 8 and 8' are, of course, correspondingly staggered. The inner ends of the coils 7 and 7' are connected by a cross wire 9, and the inner ends of the windings 8 and 8' are connected by a cross connection 10. The input terminals for the receiver are designated 11 and 12 respectively. The coils 7 and 8' are connected through a wire 13. By this arrangement of connections the windings 7 and 7' are in series, and the windings 8 and 8' are in series, while both sets of windings are continuously in series with each other.

As thus arranged, the receiver will operate most effectively on alternating currents. The windings 7 and 8 being reversed to each other in the direction of their windings but being on opposite sides of the alternating current supply wires, will tend to magnetize

the pole piece 5. In like manner, the windings 7' and 8' will operate together to magnetize the pole piece 6. At the same time, by the staggered arrangement of the coils the 5 pole piece 6 will have a magnetism induced therein of a polarity opposite to the magnetism induced in the core 5. This will mean that there will be the desired opposite polarity at the ends of the pole pieces directly 10 beneath the armature.

In the modification shown in Figure 3, a somewhat similar arrangement is employed. In this view, 14 and 15 designate associated cores or pole pieces. Wound about the core 15 are coils 16 and 17. Wound about the core 15 are windings 16' and 17'. The inner ends of the windings 16 and 16' are connected by a cross wire 18. One end of the winding 17' is connected through a diagonal cross wire 19 with the opposite end of the winding 16. One end of the winding 17 is connected through a diagonally extending cross wire 20 with the opposite end of the winding 17'.

25 The windings as thus disposed will tend to produce the desired magnetic polarity in the pole pieces 14 and 15 when the terminals 21 and 22 are connected in an alternating current circuit.

30 One manner of using a phone embodying the present invention is illustrated in Figure 4. In this figure, which is merely diagrammatic, 23 indicates a thermionic tube, which may be the last tube in a radio receiving apparatus. The thermionic tube 23 is the usual output circuit including the plate lead 24, the "B" battery 25 and the return lead 26. Connected in series with the plate lead 24 and the plate current source 25 is a choke 40 coil 27. The receiver is designated 28 and is coupled in a shunt circuit across the choke coil and source of plate current 25, the shunt circuit containing a condenser 29 which protects the telephone 28 against any direct current impulses and which serves to bypass 45 alternating current impulses generated in the shunt circuit by reason of the direct current variations in the plate or output circuit of the thermionic tube 23.

50 As thus arranged it will be seen that the telephone 28 responds only to alternating currents and that it is not biased by any direct current circuit. At the same time, the

phone circuit is inductively coupled into the output circuit of the tube whereby alternating current impulses will be impressed on the terminals of the telephone in exact accordance with the variations in the flow of current in the plate circuit of the thermionic tube. 55 60

The advantages of the present invention arise out of the fact that the windings are so arranged about the pole pieces that the phone will respond most effectively to alternating currents, and alternating currents 65 can be more efficiently used in the receiver than they can in the ordinary type of receiver arranged primarily for use in direct current circuits only.

A further advantage of the invention 70 arises out of the fact that an arrangement is provided for using an alternating current telephone receiver in an alternating current circuit without any direct current potentials being impressed thereon. 75

We claim:

1. In a telephone, a pair of pole pieces, and a pair of windings on each pole piece, one winding on each pole having an end leading to an input terminal, the other two windings 80 having an end which is connected together, the remaining ends of corresponding windings being connected by cross-over wires.

2. In a telephone, a pair of pole pieces, a pair of windings on each pole piece with the 85 turns thereof in opposite directions, the windings of similar direction on the two pole pieces being connected together, the two windings of like direction thereby being connected in series, the two groups of windings 90 also being connected in series.

3. In a telephone, a pair of pole pieces, a pair of windings on each pole piece, the windings on each pole piece being disposed at opposite ends thereof, one of the windings 95 on each pole piece being reversed to the winding on the other, the windings being reversely arranged on the two pole pieces, the windings of like direction being connected together, and all of the windings being 100 connected in series.

In testimony whereof we have hereunto set our hands.

WILLIAM S. TURNER.
ALBERT N. LONG, JR.
